INDEXING SYSTEM FOR COLOR TELEVISION
Wilson P. Boothroyd, Huntingdon Valley, Pa., assignor,
by mesne assignments, to Philco Corporation, Phila-
delphia, Pa., a corporation of Delaware
Filed Nov. 23, 1959, Ser. No. 854,711
14 Claims. (Cl. 178—5.4)

The present invention relates to electrical systems and more particularly to cathode ray tube systems comprising a beam-intercepting structure and indexing means arranged in cooperative relationship therewith which produces signals representative of the position of the beam as it scans said structure.

The invention is particularly useful in connection with color television image presentation systems and it is in connection therewith that it will be described. It is especially valuable in systems employing a cathode ray tube in which a single electron beam is produced and in which there is a beam-intercepting structure comprising image-forming and beam-indexing portions. The image-forming portion is composed of a plurality of sets of strips of fluorescent materials which are interspersed with one another in a selected order. Each set of strips is made from a material which emits light of a different selected color in response to the scanning of the electron beam thereupon. To produce a colored image the scanning beam is modulated in intensity as it scans the image-forming portion by a signal representative of the color components of a scene being televised.

To insure that the modulation of the beam is coordinated with the scanning position of the latter so that when the beam impinges upon a particular phosphor strip, say a strip emissive of red, it will be modulated by a signal whose intensity corresponds to the red content of the element then being scanned, the beam-intercepting structure also has a beam-indexing portion which may consist, for example, of a plurality of parallel indexing strips arranged in a predetermined geometrical relation to selected ones of the image-forming phosphor strips. The indexing strips are made of a material which has a response which is detectably different from the response of other parts of the beam-intercepting structure. They may be composed, for example, of a material which has a secondary-electron-emissivity which differs from the secondary-electron-emissivity of the other portions of the beam-intercepting structure. Alternatively, they may be made of a material which emits radiation in a portion of the electromagnetic wave spectrum which is different from the portions thereof occupied by the light emitted by the phosphor strips so as to assist in isolating the indexing radiation from the image radiation.

It has previously been observed that if there is only one indexing strip for each "triplet" or group of three adjacent phosphor strips, the phase of the fundamental component of the indexing signal generated by the scanning of the single beam thereupon is very susceptible not only to phase variations introduced by variations in the speed at which the beam is scanned, but also to variations in the intensity of the beam when it scans the phosphor strips intermediate the indexing strips. This latter cause of phase variation seriously impairs the effectiveness of the indexing signal in establishing the desired coordination between beam intensity and position. Previously it was known that these phase errors due to the variations in beam intensity could be reduced by deriving an indexing signal having a frequency greater than the rate at which the triplets (i.e., groups of three adjacent phosphor strips) are scanned. This indexing signal could be derived either by placing more than one indexing strip per triplet, or by providing one indexing strip per triplet and deriving a higher

2

harmonic of the signal produced when the beam scans the indexing strips.

While the use of higher index frequency did assist in minimizing appreciable variations in phase due to variations in the intensity of the beam as it scanned the beam-intercepting structure, the higher frequency indexing signal contained no readily recognizable information which denoted the absolute phase position of the generated indexing signal with respect to the scanning by the beam of phosphor strips emissive of a particular color. It has hitherto been proposed to eliminate this ambiguity by providing a set of auxiliary indexing elements in addition to the usual indexing elements. The auxiliary elements produced an auxiliary indexing signal, when impinged upon by the beam during an interval when no image was being produced, which provided absolute phase information to lock-in the oscillator (hereinafter termed the "writing oscillator") which controlled the modulation of the beam to correspond with its position on the screen.

When the beam reproduced the image, however, a primary indexing signal was generated by the scanning of the beam over the primary indexing elements which was used to synchronize the writing oscillator.

In one arrangement of this prior system the auxiliary indexing signal was derived from the scanning of relatively widely spaced auxiliary indexing strips located in a marginal portion of the beam-intercepting structure, whereas the primary indexing signal was derived by scanning of a number of closely spaced indexing strips positioned opposite the image-forming portion of the beam-intercepting structure. Since the primary indexing signal had a much higher frequency than the auxiliary indexing signal it was hitherto necessary to provide one amplifier for amplifying the primary indexing signal and another amplifier for the auxiliary indexing signal. This added to the cost and complexity of such systems.

It is therefore an object of the present invention to provide a less expensive indexing system of the type described.

Another object of the invention is to provide a less complex indexing system of the type described.

Still another object of the invention is to provide an indexing system of the type described which requires only an amplifier tuned to a single frequency.

In accordance with the invention the foregoing objects are achieved in a cathode ray system of the above described type in which auxiliary indexing elements are utilized, by providing that the indexing signals derived from scanning both the auxiliary and primary indexing elements have the same given frequency thereby permitting the use of a single amplifier constructed to amplify only said given frequency for amplifying both indexing signals. I accomplish this by modulating the beam of the cathode ray tube, when it scans the auxiliary indexing strips, by a selected signal which interacts with the signal produced by scanning of the auxiliary strips to produce an auxiliary indexing signal whose frequency is such that it can be amplified by the single amplifier. The auxiliary signal, after amplification in the indexing amplifier, is then mixed with the modulating signal thereby to produce a difference frequency at the frequency (hereinafter termed the "writing" frequency) at which the single beam is to be modulated by color-representative signals when the beam scans the image-forming portion of the screen. This difference signal will have a phase which is determined by the scanning of the auxiliary indexing strips and is used as a first synchronizing signal, during an interval in which pictorial intelligence is not being reproduced, to lock the phase of the writing oscillator so that its output signal, at the beginning of each line, has an absolute phase determined by the scanning of the auxiliary strips.

When the beam starts to scan the image-forming portion of the screen opposite which the primary indexing elements are disposed, means are provided for cutting off the modulating signal whereupon the difference signal is not produced. The primary indexing elements are so disposed that when scanned by the beam a primary indexing signal having the frequency passed by the single amplifier is produced which then is processed to produce a second synchronizing signal at the writing frequency. The second signal is used, during the scanning of the image-forming portion, to control the phase of the writing oscillator output signal (whose initial phase was established absolutely by the auxiliary indexing signal) so that when the beam impinges on a strip emissive of a particular color it will contemporaneously be modulated by a signal representative of that color. The manner in which this is accomplished will be described in detail below.

In a preferred embodiment of the invention there is provided a single indexing amplifier which is constructed to pass a signal having a frequency

$$\frac{m}{n} f_w$$

where m and n are integers higher than 1,

$$\frac{m}{n}$$

is greater than unity and f_w is the "writing frequency" at which the beam is to be modulated by image-representative signals when it scans the image-forming portion of the screen. In a marginal portion of the beam-intercepting structure a set of auxiliary indexing strips are located which, if scanned by an unmodulated beam at a normal speed would produce an indexing signal having a frequency f_w , i.e., the "writing" frequency. During the scanning of the auxiliary indexing strips just prior to the reproduction of each line of the image, the beam is modulated by an oscillatory wave having a frequency

$$\left(\frac{m}{n}-1\right) f_w$$

When the modulated beam impinges on the auxiliary indexing strips, a resultant auxiliary indexing signal is produced which has a frequency

$$\frac{m}{n} f_w$$

which can accordingly be amplified by the single indexing amplifier.

The amplified auxiliary indexing signal

$$\frac{m}{n} f_w$$

is then heterodyned with the modulating signal

$$\left(\frac{m}{n}-1\right) f_w$$

and the difference signal f_w is extracted which has a phase determined by the scanning of the auxiliary indexing strips and which is used to lock the phase of the writing oscillator output signal thereto. In so doing, the initial phase of the output signal of the writing oscillator is established just before each line is scanned.

The initial phase of the oscillatory signal is subsequently changed when the beam scans the primary indexing elements in reproducing the pictorial information of each line primarily because of variations in the rate at which the beam is deflected over the primary indexing elements associated with the image-forming portion of the screen structure. These phase changes are utilized to coordinate beam modulation with beam position so as to obtain faithful color reproduction.

To measure these variations in the beam scanning velocity a plurality of primary indexing strips are disposed opposite the image-forming portion of the screen

being spaced relatively close to one another so as to minimize variations in the phase of the primary indexing signal which arise from changes in the beam intensity. Their spacing is such that when an unmodulated beam traverses them at a normal speed, a signal is produced having a frequency

$$\frac{m}{n} f_w$$

the frequency of the signal amplified by the single indexing amplifier.

When the beam scans the primary indexing strips during the picture portion, the modulating signal is cut off and a primary indexing signal

$$\frac{m}{n} f_w$$

is produced. Since it is desired, during the scanning of the picture, to control the phase of the writing oscillator by the phase of the primary indexing signal, the primary indexing signal is amplified and then is multiplied by n in a conventional multiplier which produces an output signal having a frequency mf_w . Simultaneously, the output signal of the writing oscillator at the writing frequency f_w is multiplied by $(m-1)$ to produce a signal having a frequency $(m-1)f_w$. These two multiplied signals, mf_w and $(m-1)f_w$, are then heterodyned together to produce a difference signal at the writing frequency f_w whose phase is used to lock the phase of the output signal of the writing oscillator during the scanning of the image-forming portion of the screen. As the phase of the primary indexing signal changes because of variations in the beam scanning rate, the phase of the output signal of the writing oscillator correspondingly changes so that the modulation of the beam intensity during the scanning of the image-forming portion is coordinated with the beam position.

The invention will be described in greater detail with reference to the appended drawings forming part of the specification and in which:

FIG. 1 is a block diagram, partly schematic, showing one form of a cathode ray tube system in accordance with the invention; and

FIG. 2 is a sectional view of a beam-intercepting structure suitable for the cathode ray tube system shown in FIG. 1.

Referring to FIGURE 1, a cathode ray tube system is shown therein which comprises a cathode ray tube 10 containing a cathode 12, a control grid 14, a beam-focussing electrode 16, and a beam-accelerating electrode 18 consisting of a conductive coating on the inner wall of the envelope of the tube 10 to which an appropriate high positive value of voltage on the order of, for example, 30 kv. is applied. A single beam 13 is emitted from the cathode 12 and is accelerated toward a beam-intercepting structure 26 which is shown in greater detail in FIG. 2. The beam 13 is deflected by a conventional deflection yoke 20 which encircles the neck of the tube at the point where it joins the flared portion therof. The yoke 20 is energized in a conventional manner by appropriate deflection signals from the vertical and horizontal deflection circuits 24 which are themselves energized by appropriate synchronizing signals removed from the incoming signals by conventional synchronizing circuits (not shown).

In the arrangement shown in FIGS. 1 and 2, the beam-intercepting structure 26 is formed directly on the faceplate 28 of the tube 10 although it may alternatively be formed on a suitable light-transparent substrate which is independent of, and spaced from, the faceplate 28. A plurality of sets of phosphor strips 30, 32 and 34, which are emissive of red, green and blue light respectively in response to the impingement of electrons thereupon, are arrayed on the faceplate 28 transverse to the direction in which the beam 13 is scanned. These phosphor strips are substantially rectilinear and may be spaced from

one another if desired. The materials and fabricating techniques used in constructing these phosphor strips are well known and therefore further explanation thereof is deemed unnecessary. On the rear surface of the strips 30, 32 and 34 is deposited an electron-permeable and conductive coating 36 which may consist of a layer of aluminum, for example, which reflects light and therefore helps to increase the brightness of the image produced by the phosphor strips in front of it. This layer 36 also helps to prevent the common discoloration of phosphor screen structures by negative ions known as "ion spot." A positive potential of about 25 kv. is applied to layer 36 from batteries as shown.

In the marginal (non-image-forming) portion 38 of the screen structure 26 shown in FIG. 2 a plurality of auxiliary indexing strips 40 are located. In the image-forming portion 42 of the structure 26 primary indexing strips 44 are disposed. Both pluralities of indexing strips are disposed essentially parallel to the phosphor strips. These indexing strips, when scanned by the beam 13, release large numbers of secondary-electrons which are attracted toward the highly positive electrode 18 whereupon the indexing strips and the layer 36 are driven more positive. A conductive ring 29 encircles the rim of the faceplate 28 and the changes in the charge of the layer 36 create a displacement current in the ring 29 which is passed through a condenser 33 thereby generating indexing signals which indicate the relative lateral displacement of the beam 13. The indexing signals are applied to the single indexing amplifier 50 which amplifies substantially only a single frequency, i.e.,

$$\frac{m}{n} f_w$$

For illustrative purposes it will be assumed that $m=5$, $n=3$ and f_w , the "writing frequency," is 6.4 mc.

The number of auxiliary strips 40 per given unit of space measured in the direction of scanning is such that, scanned at the normal speed by an unmodulated beam, they would produce a signal having a frequency f_w and a phase ϕ_1 . This signal, it will be noted, cannot be amplified by the indexing amplifier 50. It is therefore necessary to derive, during the scanning of strips 40, indexing signals which can be amplified in amplifier 50.

Operation of Auxiliary Indexing Circuit

It has previously been stated that it is desired to lock-in the output signal of the writing oscillator to an absolute phase determined by the scanning of auxiliary indexing strips such as the strips 40 on the beam-intercepting structure. This is accomplished by the apparatus shown within the dashed-line rectangle 80, i.e., the auxiliary indexing circuit. This circuit derives a signal from the scanning of the strips 40 which can be amplified by the single indexing amplifier 50 and from which a signal at the writing frequency may be derived whose phase can be used to establish the absolute phase of the output signal of the locked oscillator 56 during the scanning of the pre-picture portion 38.

In order to provide the latter phase-synchronizing signal the beam 13 is modulated during the pre-picture scanning period by a signal whose frequency is such that when it interacts with the signal produced by the scanning of the auxiliary indexing strips 40 a resultant output signal having a frequency within the pass band of the indexing amplifier 50 will appear across condenser 33, namely a signal

$$\frac{m}{n} f_w (10.61 \text{ mc.})$$

Oscillator 52, which may be of conventional construction, supplies a modulating signal

$$\left(\frac{m}{n} - 1 \right) f_w / \phi_0 \quad (1)$$

(i.e., 4.2 mc.), where ϕ_0 is the phase of the free-running oscillator 52 output signal, to the grid 14 only when a gating pulse is supplied from a conventional gate pulse generator 58 to the oscillator 52 during the horizontal blanking pulse interval. The gate pulse generator 58 which may be a multivibrator circuit, for example, is triggered by pulses derived from the horizontal deflection synchronizing circuit (not shown). When the modulated beam 13 traverses the auxiliary indexing strips 40, the modulating signal

$$\left(\frac{m}{n} - 1 \right) f_w / \phi_0$$

and the signal

$$f_w / \phi_1 \quad (2)$$

produced by the beam's impingement on strips 40 will combine to produce a sum signal

$$\frac{m}{n} f_w / \phi_0 + \phi_1 \quad (3)$$

which has a frequency 10.61 mc. which can be amplified in the indexing amplifier 50. The amplified sum signal at 10.61 mc. is then mixed with the modulating signal (Expression 1) from oscillator 52 in a conventional mixer 54. In the output circuit of the latter will appear a difference signal at 6.4 mc., i.e.,

$$\left[\left(\frac{m}{n} f_w / \phi_0 + \phi_1 \right) \right] - \left[\left(\frac{m}{n} - 1 \right) f_w / \phi_0 \right] = f_w / \phi_1 \quad (4)$$

It will thus be seen that the mixer 54 produces an output signal at the writing frequency having a phase determined by the rate of scanning of the auxiliary indexing strips 40 in the pre-picture portion 38. This signal is applied to the writing oscillator 56 only during the scanning of the pre-picture portion 38 to synchronize the phase of the writing oscillator 56 therewith.

It has been shown that in the period prior to the beginning of the scanning of each line the writing oscillator 56 has been locked to the phase of the signal

$$f_w / \phi_1$$

(Expression 2). If there are variations in the rate of scanning of the image-forming portion 42 it is also necessary to synchronize the phase of the oscillator 56 to correspond therewith so that the colors of the image will be faithfully reproduced. Accordingly there are disposed in portion 42 of the structure 26 the primary indexing strips 44 which are spaced much closer to one another than are the strips 40 in the marginal portion 38. There are

$$\frac{m}{n}$$

as many strips 44 as there are strips 40 within a given unit of space as measured in the direction of scanning. If the elements 44 were scanned by an unmodulated electron beam at its normal scanning speed a signal

$$\frac{m}{n} f_w (10.61 \text{ mc.})$$

would be produced across resistor 31. However, to lock the oscillator 56 during the scanning of the picture portion 42 there must be supplied to the writing oscillator 56 a second indexing signal at the writing frequency f_w (6.4 mc.).

Operation of Primary Indexing Circuit

Apparatus is shown within the dashed-line rectangle 90 for deriving this second phase-synchronizing signal. During the scanning of the picture portion 42 the oscillator 52 is cut off by a pulse from the gate pulse generator 58. A pulse of opposite polarity is also applied to mixer 64 from generator 58 to permit the mixer to supply its out-

put signal to oscillator 56. When the beam scans the strips 44 a primary indexing signal

$$\frac{m}{n} f_w / \frac{m}{n} \phi_1 \quad (5)$$

is produced which is applied to the amplifier 50 via the coupling capacitor 33. It should be noted that this signal may be considered as having a phase which is 5/3 that of the phase of the signal produced by the scanning of the auxiliary indexing strips 40 and bears a constant relation to the latter, i.e. the scanning of the first and alternate primary indexing strips 44 produces signal peaks which are separated from one another by the same amount of time as the peaks produced in scanning the auxiliary strips 40 are separated from one another. Furthermore the first peak of the primary indexing signal is separated from the last peak of the auxiliary signal by the same amount as the peaks of the auxiliary signal are separated from one another.

The primary indexing signal is amplified in amplifier 50 and is then applied to a frequency multiplier 60 of conventional construction where it is multiplied by a factor n thereby producing a signal (31.83 mc.) which may be expressed as

$$m f_w / m \phi_1 \quad (6)$$

At the same time the output wave $f_w + \phi_1$ of the oscillator 56 is multiplied in a conventional multiplier 62 by $(m-1)$ to produce a signal

$$(m-1) f_w / \phi_1 \quad (7)$$

i.e., 25.6 mc. The 31.83 mc. and the 25.6 mc. signal are applied to a conventional mixer 64 which produces a difference signal

$$f_w / \phi_1$$

(6.2 mc.) in its output which contains phase information relating to the rate of scanning of the strips 44. This difference signal is applied to oscillator 56 only during the scanning of the image-forming portion 42 in which the primary indexing strips 44 are located, and controls the phase of the output signal of the latter oscillator thereby.

Beam Modulation Processing Circuit

It has already been shown how the writing oscillator 56 is locked to the phase of a first synchronizing signal having the writing frequency f_w and a phase determined by the scanning of the auxiliary strips 40 during the pre-picture portion 38, and is locked to the phase of a second synchronizing signal at the writing frequency f_w during the scanning of the indexing strips 44 during the picture portion 42. The second synchronizing signal adjusts the phase of the oscillator 56 to accord with its instantaneous position measured in a horizontal direction so that modulation of the beam by image signals representative of colors emitted by the phosphor strips then being scanned is effected.

FIG. 1 discloses one of several ways in which this coordination may be accomplished. Apparatus is shown in the dash-line rectangle 95 for producing a signal at the writing frequency f_w , which modulates the beam when the portion 42 is scanned. This signal has a phase which depends on the phase of the output signal of the writing oscillator 56, and on the difference between the phase of the reference subcarrier and the instantaneous phase of the received chrominance components which comprise a phase and amplitude modulated subcarrier. To derive such a signal the output signal (Expression 6) of the multiplier 60 is mixed with the chrominance components

$$f_c / \phi_c$$

of the incoming signal in a conventional mixer 66. In the output of the mixer 66 a difference signal

$$m f_w - f_c / m \phi_1 - \phi_c \quad (8)$$

5 will appear which has an amplitude which depends on the amplitude of the received chrominance components.

Simultaneously the output signal of the multiplier 62 (Expression 7) is mixed in mixer 68 with the reference signal

$$f_c / \phi_r$$

where ϕ_r is the phase of the incoming "burst" of the color subcarrier, to produce a difference signal

$$m f_w - f_w - f_c / m \phi_1 - \phi_1 - \phi_r \quad (9)$$

15 This difference signal is then mixed with the output signal (Expression 8) of the mixer 66 to produce another difference signal

$$f_w / \phi_1 + \phi_r - \phi_c \quad (10)$$

20 which is at the writing frequency and has a phase determined by the phase (ϕ_1) of the scanning of the primary indexing elements 44, the instantaneous phase (ϕ_c) of the color modulated subcarrier, and the phase (ϕ_r) of the reference wave. When this signal is applied to the grid 14, together with the luminance signal from the luminance channel (not shown), to modulate the beam 13, colored scenes will be reproduced with fidelity.

Many other variations of the system shown in FIG. 1 are possible. For example, if the writing frequency desired is 6.5 mc., the auxiliary indexing strips would be so arranged as to generate a signal at 3.2 mc. whereas the primary indexing strips would generate a signal at 9.6 mc. when they are scanned by an unmodulated electron beam at normal speed. The single indexing amplifier would be tuned to 9.6 mc. and when the beam scanned the auxiliary indexing strips it would be modulated by an oscillatory wave having a frequency of 6.4 mc. As a result of the interaction of this modulating signal and the signal generated by the scanning of the auxiliary indexing strips, a sum signal at 9.6 mc. (i.e., 6.4+3.2 mc.) is produced which is amplified by the single indexing amplifier and mixed with the beam modulating wave at 6.4 to produce a difference signal at 3.2 mc. This difference signal is then doubled in frequency to produce a signal at 6.4 mc. which is used to control the writing oscillator during the pre-picture interval. In this case the writing oscillator may be the same as the oscillator which modulates the beam when it scans the auxiliary indexing strips.

50 When the beam scanned the primary indexing strips it would not be modulated by the 6.4 mc. wave. A primary indexing signal at 9.6 mc. is produced at the input to the single amplifier which thereupon produces an amplified output signal at 9.6 mc. which is mixed with the output wave of the oscillator at 6.4 mc. to produce a difference frequency signal at 3.2 mc. This difference signal is then doubled to produce a second 6.4 mc. signal for synchronizing the phase of the writing oscillator during the scanning of the picture portion of the beam-inter-60 cepting structure.

Still other systems are possible which would employ the present invention, as for example, one in which the auxiliary indexing strips are so disposed as to produce a signal at 6.4 mc. when scanned by an unmodulated beam and wherein the primary indexing strips are arranged to produce a signal at 9.6 mc. The beam is modulated by a 16 mc. signal as it scans the auxiliary indexing strips and a difference signal at 9.6 mc. is derived therefrom. A single indexing amplifier tuned to 9.6 mc. amplifies the auxiliary indexing signal which is then mixed with the 16 mc. modulating signal to produce a first synchronizing signal at 6.4 mc. for locking the phase of the writing oscillator thereto. On the other hand, when the beam scans the primary indexing strips the beam is not modulated by the 16 mc. signal and the primary indexing

signal at 9.6 mc. is produced and amplified. It is then heterodyned with the 16 mc. signal to produce a second synchronizing signal at 6.4 mc. for locking the phase of the writing oscillator output signal thereto.

In all of these variations only one amplifier tuned to a single frequency is necessary to produce excellent results insofar as the proper functioning of the indexing system is concerned.

What is claimed is:

1. A cathode ray tube system comprising: a cathode ray tube having means for producing an electron beam therein, a beam-intercepting structure comprising first and second pluralities of indexing elements, means for deflecting said beam over said intercepting structure at a predetermined velocity, said first and second pluralities of indexing elements having respectively different periodicities to produce, in response to electrons impinging thereupon, first and second signals having respective first and second nominal frequencies, a single means for amplifying only signals generated in the scanning of said elements which have said second nominal frequency, and means for modifying said beam when it scans said first plurality of elements so that when the latter elements are scanned they generate a signal having substantially said second nominal frequency.

2. A cathode ray tube system according to claim 1 wherein said beam-modifying means includes means for modulating said beam by a modulating signal substantially only when said first plurality of elements are scanned, said modulating signal having a frequency such that it interacts with the signal generated by scanning said first plurality of elements to produce a signal having substantially said second nominal frequency.

3. A cathode ray tube system comprising: a cathode ray tube containing means for producing an electron beam, a beam-intercepting structure comprising a first plurality of indexing elements which recur with a given periodicity, and a second plurality of indexing elements which recur at a periodicity which is a fractional multiple of said first periodicity, means for scanning said beam over said structure thereby to produce first and second indexing signals corresponding respectively to the rates at which said first and second pluralities are traversed by said beam, said second signal having substantially a predetermined nominal frequency, means for modulating said beam by a first modulating signal substantially only as it traverses said first plurality of indexing elements whereupon said first modulating signal and said first indexing signal interact to produce a first difference frequency signal at said nominal frequency, a single amplifying means which amplifies said first difference frequency signal and said second indexing signal, said amplifying means being constructed to amplify substantially only signals at said nominal frequency, means for producing an oscillatory wave, means responsive to said first modulating signal and to said amplified first difference frequency signal for applying a first synchronizing signal to said oscillating means during the scanning of said first plurality of indexing elements thereby to control the frequency of said oscillatory wave, means for multiplying the frequency of said amplified second indexing signal to produce a first product frequency signal, means for multiplying the frequency of said oscillatory wave to produce a second product frequency signal, and means responsive to said first and second product frequency signals for supplying to said oscillating means a second synchronizing signal having the same frequency as said first synchronizing signal substantially only when said beam scans said second plurality of indexing elements.

4. A cathode ray tube system comprising: a cathode ray tube containing means for producing an electron beam therein, a beam-intercepting structure comprising a plurality of image-forming elements and a beam-indexing portion in a predetermined spatial relation thereto, said indexing portion including an auxiliary indexing portion

containing a relatively low number of auxiliary indexing elements per unit of space measured in a direction transverse to the axes of said elements, said indexing portion also including a primary indexing portion containing

$$\frac{m}{n}$$

times as many primary indexing elements as said auxiliary portion contains per said unit of space, where m and n are integers greater than 1 and

$$\frac{m}{n}$$

is greater than 1, means for deflecting said beam over said auxiliary and primary indexing portions, the impingement of said beam on said primary portion causing the generation of a primary indexing signal having a frequency

$$\frac{m}{n}f$$

where f is a predetermined frequency, means for modulating said beam at a frequency

$$\left(\frac{m}{n}-1\right)f$$

when said beam is deflected over said auxiliary portion, the interaction of the modulation of said beam and the signal resulting from the impingement of said beam on said auxiliary portion producing an auxiliary indexing signal having a frequency

$$\frac{m}{n}f$$

means for amplifying both said primary and auxiliary indexing signals, said amplifying means being constructed to amplify substantially only signals having a frequency

$$\frac{m}{n}f$$

means for combining the amplified auxiliary indexing signal with a signal

$$\left(\frac{m}{n}-1\right)f$$

45 from said modulating means to produce a first synchronizing signal substantially at a frequency f , an oscillator for producing an output wave substantially at said frequency f , means for supplying said first synchronizing signal f to synchronize said oscillator substantially only when said beam scans said auxiliary indexing portion, means for multiplying said primary indexing signal by n to produce a signal having a frequency mf , means for multiplying the output wave of said oscillator by $(m-1)$ to produce a signal having a frequency $(m-1)f$, means for combining said signals mf and $(m-1)f$ to produce a second synchronizing signal having a frequency f , and means for applying said second synchronizing signal to said oscillator to synchronize the latter substantially only when said beam scans said primary indexing elements.

50 5. In a color image-producing system, a color image-producing cathode ray tube having an image screen to be scanned line-by-line by an electron beam within the tube, means for effecting the scanning motion of the electron beam, means for modulating the electron beam with a signal representative of color content of the image to be produced, two sets of indexing elements on said screen, which sets are scanned successively by said beam and have respectively different periodicities, one set of indexing elements producing an indexing signal having a predetermined nominal frequency as the elements are scanned by said beam, means for modifying said beam during its scanning of the other set of indexing elements so that the latter produce another indexing signal having the same nominal frequency as said first indexing signal, common

55 70 amplifier means for amplifying both of said indexing sig-

nals, and means for utilizing the amplified signals to effect proper time coordination between color signal modulation and position of said beam.

6. A color image-producing system according to claim 5, wherein an oscillator controls the color signal modulation of said beam, and the amplified indexing signals are utilized to control said oscillator.

7. A color image-producing system according to claim 5, wherein the means for modifying said beam during its scanning of the other set of indexing elements comprises an oscillator and means for turning the oscillator on during the scanning of said other set of indexing elements.

8. In a color image-producing system for a color television receiver which receives a color television signal including a chrominance component, a color image-producing cathode ray tube having an image screen to be scanned line-by-line by an electron beam within the tube, means for effecting the scanning motion of the electron beam, colored light-emissive elements on said screen which successively and repetitively emit light of different colors in response to electron beam impingement during each line scan, means for effecting chrominance modulation of said beam according to said chrominance component, two sets of indexing elements on said screen, which sets are scanned successively by said beam and have respectively different periodicities, one set of indexing elements producing an indexing signal having a predetermined nominal frequency as the elements are scanned by said beam, means for modifying said beam during its scanning of the other set of indexing elements so that the latter produce another indexing signal having the same nominal frequency as said first indexing signal, common amplifier means for amplifying both of said indexing signals, and means for utilizing the amplified indexing signals to effect proper time coordination between chrominance modulation and position of said beam.

9. In a color image-producing system for a color television receiver which receives a color television signal including a chrominance component, a color image-producing cathode ray tube having an image screen to be scanned line-by-line by an electron beam within the tube, means for effecting the scanning motion of the electron beam, colored light-emissive elements on said screen which successively and repetitively emit light of different colors in response to electron beam impingement during each line scan, means for effecting chrominance modulation of said beam according to said chrominance component, a first set of indexing elements on a pre-image portion of said screen, a second set of indexing elements on an image-forming portion of said screen, said sets of elements having respectively different periodicities, said second set of elements producing an indexing signal having a predetermined nominal frequency as the elements are scanned by said beam, means for modifying said beam during its scanning of said first set of elements so that the latter produce another indexing signal having the same nominal frequency as said first indexing signal, common amplifier means for amplifying both of said indexing signals, and

means for utilizing the amplified indexing signals to effect proper time coordination between chrominance modulation and position of said beam.

10. A color image-producing system according to claim 9, wherein the means for effecting chrominance modulation of said beam includes an oscillator, the indexing signal produced by beam scanning of said first set of elements is utilized to phase said oscillator at the start of each line scan, and the indexing signal produced by beam scanning of said second set of elements is utilized to control the phase of the oscillator during each line scan of the image-forming portion of said screen.

11. A color image-producing system according to claim 9, wherein a beam-modulating oscillator is provided and is turned on only during the beam scanning of said first set of elements to cause production of said other indexing signal.

12. A color image-producing system according to claim 9, wherein the means for effecting chrominance modulation of said beam includes an oscillator, said system further comprising means for producing from said other indexing signal a first signal for synchronizing said oscillator during beam scanning of said first set of elements, and means for producing from said first indexing signal a second signal for synchronizing said oscillator during beam scanning of said second set of elements.

13. In a cathode ray tube system, a cathode ray tube having means for producing an electron beam thereto, a beam-intercepting structure comprising first and second pluralities of indexing elements having respectively different periodicities, means for deflecting said beam over said structure, said second plurality of indexing elements producing a signal having substantially a given frequency when scanned by said beam, means for modulating said beam during its scanning of said first plurality of indexing elements to produce another signal having substantially said given frequency, a single means responsive to signals substantially at said given frequency for amplifying said two produced signals, means coupled to said beam-modulating means and to said single amplifying means for producing a third signal having a frequency different from said given frequency whenever said beam scans said first plurality of elements, and means cooperating with said single amplifying means for producing a fourth signal at said different frequency in response to the scanning by said beam of said second plurality of indexing elements.

14. A cathode ray tube system according to claim 13, further including an oscillator operable at said different frequency, and means for supplying said third and fourth signals to said oscillator to synchronize the latter.
